WELL PUMP

Frank C. Kniss and Richard N. Vickers, Smackover, Ark.

Application March 17, 1936, Serial No. 69,368

6 Claims. (Cl. 103—155)

This invention relates to an improved well pump and more particularly to a pump for use in deep wells. One object of the invention is to provide an improved valve structure adapted to 5 be mounted in the bottom of a well at the lower end of the well tubing where it will be immersed in oil or other liquid and serve very effectively to permit the oil to be forced upwardly through the well tubing and out at the upper end or top 10 of the well.

Another object of the invention is to provide a valve structure wherein the valve casing which is carried at the lower end of the well tube is formed with passages or ducts through which a large 15 quantity of oil may be forced during reciprocation of the pump. It will thus be seen that when this improved valve is in use, large quantities of oil may be forced upwardly through the well tube or casing and a good flow of oil assured.

Another object of the invention is to provide 20 an improved core for the valve casing which carries valve balls for controlling directional flow of oil or other liquid through the core and valve casing and to further provide the core with sealing members having close contacting engagement with walls of the bore of the valve casing so that during operation of the pump, oil will follow a predetermined path and enter and leave the valve casing correctly.

Another object of the invention is to so construct the core of the valve that it will be firmly held in place within the valve casing but may be withdrawn as a unit when cleaning, repairs or replacements are necessary.

The invention is illustrated in the accompanying drawing, wherein—

Figure 1 is a sectional view taken longitudinally through the improved valve.

Figure 2 is a sectional view taken transversely 40 through Figure 1 along the line 2—2.

Figure 3 is a sectional view taken along the line 3—3 of Figure 1.

Figure 4 is a sectional view taken transversely 45 through Figure 1 along the line 4—4.

The standing valve which is shown in longitudinal section in Figure 1 has a cylindrical casing 1 and may be of any length and diameter desired. The bore 2 of the casing is of an even diameter throughout substantially the entire 50 length of the casing but has its upper end portion enlarged and internally threaded, as shown at 3, to provide a socket by means of which the standing valve may be attached at the lower end of a well tube in the usual manner. It will thus be seen that the standing valve will be mounted

at the lower end of the well tube or casing and will be immersed in a body of oil at the bottom of a well. Ducts 4 and 5 are formed longitudinally of the valve casing 1 in opposed portions of walls of the casing, as shown clearly in Figures 2 5 and 3, and referring to Figure 1 it will be seen that these ducts are off-set longitudinally of the valve casing, the duct 4 extending downwardly for approximately half its length below the lower end of the duct 5 and at its lower end having an 10 inlet port 6 communicating with the bore 2 in spaced relation to the lower end thereof. The upper end of the duct 4 is also formed with a port 7 communicating with the bore 2 substantially midway the ports 8 and 9 of upper and 15 lower ends of the duct 5 and attention is called to the fact that the port 8 at the upper end of the duct or passage 5 communicates with the bore 2 at the bottom of the socket 3. This portion 10 of the bore 2 with which the port 8 communicates is enlarged diametrically and provides a chamber into which oil passes from the duct or passage 5 and then upwardly through the valve casing to which the standing valve is 20 attached.

The core of the valve fits snugly within the bore 2 of the casing 1 and extends longitudinally therein for substantially its entire length. This core is formed of sections and has an upper section 11, a lower section 12 and a series of intermediate sections connected in end to end engagement with the end section and to each other. The upper section 11 is of tubular formation and has its upper end portion externally threaded to form a neck 13 of a diameter to be screwed into an internally threaded socket 14 formed at the lower end of a coupling 15 which connects the core of the standing valve with a vertically disposed reciprocating pump 16 having a construction substantially corresponding to that disclosed 30 in Patent No. 1,807,741, issued June 2, 1931. At the base or lower end of the neck 13 an outstanding collar or annular flange 17 is formed about the section 11. This flange serves not only as an abutment for the lower end of the 40 socket 14 to insure a tight fit but also constitutes an outstanding annular support which rests upon the beveled face or seat 18 at the bottom of the chamber 10 and serves to maintain the core in its proper position in the valve casing and prevent it from sliding downwardly beyond the position shown in Figure 1. Packing rings 19, which are formed of compressible material, fit snugly about the section 11 under the flange 17 with a metal ring 20 between them and when the sec- 50

tion 21 of the core is screwed upon the threaded lower end portion 22 of the section 11, the packing rings 19 will be compressed and thus cause them to have tight fit against walls of the bore 2 between the chamber 18 and the port 7 at the upper end of the duct 4. The section 21 which is disposed at the level of the upper end of the duct 4 is in the form of a cage having side openings 23 so that communication will be established between the duct 4 and the bore or passage 24 of the upper section 11 and oil may move through the duct 4 and the passage 24 in a manner to be hereinafter specifically set forth when the reciprocating pump is in operation.

15 The upper one of the intermediate sections, which is indicated by the numeral 25, has a solid upper portion which is screwed into the lower end of the cage or coupling 21 and the lower portion 26 of this intermediate section is diametrically enlarged and formed hollow to provide a cage 27 having side openings or passages 28 disposed opposite the lower end of the duct 5 in registering relation to its lower port 9. Packing rings 29 which are spaced from each other 20 by a metal ring 30, fit about the solid upper portion of the section 25 between the circumferentially extending shoulder formed by the upper end of the enlarged lower portion 26 of the section and the lower end of the coupling 21. These 25 packing rings are compressed when the section 25 is screwed into the lower end of the cage or coupling 21 and have tight fitting contact with walls of the bore 2 between the port 7 at the upper end of the duct 4 and the port 9 at the lower end of the duct 5. It will thus be seen that oil 30 cannot pass through the bore 2 between the port 7 and the port 9. The cage 26 constitutes a guard or housing for a valve ball 31 which fits loosely within the cage and is movable into and out of 35 engagement with the valve seat 32 which is in the form of a nipple and mounted in the lower end portion of the cage where it is firmly held in place when the externally threaded upper end portion 33 of the section 34 is screwed into the 40 internally threaded lower end portion of the section 25. This section 34 is of tubular formation and has its intermediate portion externally thickened to form an outstanding annular shoulder 35 serving as an abutment for the upper one of a 45 pair of sealing rings 36 which fit about the section 34 with a metal ring 37 between them. The packing rings 36 are compressed when the cage or section 38 is screwed tightly upon the threaded lower end of the section 34 and have tight 50 contacting engagement with walls of the bore 2 to prevent flow of oil through this portion of the bore 2 between the port 6 at the lower end of the duct 4 and the port 9 at the lower end of the duct 5. Since the section 34 is of tubular formation, 55 oil may flow through it at certain periods during operation of the pump. This cage 38 has its lower end in threaded engagement with the upper end of the lower section 12 of the core and within the lower end portion of the section 38 60 is mounted a valve seat 39 which has the form of a nipple so that oil may flow upwardly through the bore 40 of the section 12 and through the valve seat 39 and the cage to enter the lower end of the duct 4. The valve ball 41 which fits 65 loosely in the cage 38 normally rests upon the valve seat 39 but may be moved upwardly to a raised position in which it bears against the seat 42 and permit oil to flow from the cage through its side port 43 and enter the duct 4 70 through the port 6 at the lower end thereof.

Packing rings 44 having a metal ring 45 between them fit about the lower section 12 and maintained in place thereon by a sleeve nut 46 which when screwed into place causes the packing rings to be expanded and have tight fitting engagement with walls of the bore 2. Therefore, the portion of the bore 2 between the lower end of the duct 4 and the lower end of the valve casing will be sealed and oil prevented from flowing upwardly except through the bore 40 of the section 12.

When this improved pump is in use the valve casing is connected with the lower end of the well tubing or casing so that it extends down into the body of oil at the bottom of a well. The pump rod is disposed vertically in the well in the usual manner with its lower end connected with the reciprocating pump 16 and its upper end operatively connected with the usual walking beam so that reciprocating motion will be imparted to the pump. As the reciprocating portion of the pump is drawn upwardly, oil is sucked upwardly into the standing valve and passes upwardly through the bore 40 of the lower section 12. This moving column of oil unseats the valve 25 41 and flows out through the by-passages 43 of the cage 38 to enter the duct 4 through the port 6 at its lower end and then passes upwardly through the duct 4. Upon reaching the upper end of the duct 4, the oil enters the cage or 30 coupling 21 through the side ports or passages 23 thereof and passes upwardly through the bore 24 of the upper section 11 and into the body of the pump. The valve ball 41 when moved upwardly seats against the valve seat 42 so 35 that the bore 47 of the section 34 is substantially closed and, therefore, the valve ball 31 remains in its lowered position in which it is seated upon the valve seat 32 and shuts off communication between the bore 47 and the duct 5. Upon 40 downward movement of the reciprocating portion of the pump, the oil which has been drawn upwardly is forced downwardly through the upper section 11 and the duct 4 into the cage 38 and as the valve ball 41 will now be seated upon 45 the valve seat 39 to prevent flow of the oil back through the bore 40 of the lower section into the well, the oil will pass upwardly through the bore 47 of the section 34 and unseat the valve ball 31 so that it may flow upwardly through 50 the cage 26 and the duct 5 into the chamber 18 from which it will flow upwardly through the valve casing to the upper end of the well. The reciprocating portion of the pump will then again move upwardly to draw another charge of oil 55 from the well and as the valve ball 31 will have returned to its lowered or seated position, oil will be prevented from flowing downwardly through the duct 35 from the well casing. Another downward movement of the reciprocating 60 portion of the pump will force the charge of oil just withdrawn from the well upwardly through the section 31 and duct 35 into the well casing or tubing. It will thus be seen that during operation of the pump, successive charges 65 of oil will be drawn from the well and then forced upwardly through the duct 5 and the well tubing or casing. The ducts 4 and 5 are quite large as can be seen by referring to Figures 2, 3 and 4, and therefore a large quantity of oil can be easily 70 drawn through the standing valve during upward movement of the reciprocating portion of the pump and quickly forced out of the standing valve into the well tubing during a downward movement of the reciprocating portion of the 75

pump. When it is necessary to clean the standing valve or repair or replace any of the elements forming its core, this can be easily done after withdrawing the standing valve from the well as 5 the core may then be withdrawn as a unit from the valve casing and then be very easily taken apart and reassembled after it has been thoroughly cleaned and any parts repaired or new parts substituted if necessary.

10 Having thus described the invention, what is claimed as new is:

1. In a standing valve, a tubular casing having its upper end adapted for connection with the lower end of a well tube, walls of the valve casing being formed with upper and lower longitudinally extending ducts offset relative to each other longitudinally of the valve casing to stagger the ducts and dispose their ends out of opposed relation to each other, a core fitting in the bore 20 of the tubular valve casing and formed with a bore open at its lower end and having side ports communicating with lower ends of both ducts and with the upper end of the lower duct, the bore of said core being blocked between the upper end of the lower duct and the lower end of the upper duct and the upper duct having its upper end opening directly into the casing, said core having its upper end adapted for connection with a reciprocating pump serving as a closure for the upper end of its bore, and valve members carried by said core for controlling directional flow of liquid through the core and ducts.

2. A standing valve for a pump comprising a tubular casing formed with upper and lower longitudinally extending ducts having their ends opening into the bore of the casing, the ducts being offset longitudinally of the casing to dispose the ducts in staggered relation to each other and position their ends out of opposed relation to each other, a hollow core fitting into the bore of said casing and formed with side ports spaced from each other longitudinally of the core and communicating with the lower end of the upper duct and the upper and lower ends of the lower duct, a barrier in said core between the ports communicating with the lower end of the upper duct and the upper end of the lower duct, and valve members carried by said core in cooperating relation to the ports communicating with lower ends of the upper and lower ducts for controlling directional flow of fluid through the core and ducts.

3. A standing valve for a pump comprising a tubular casing having longitudinally extending ducts offset longitudinally of the casing to dispose ends of an upper duct out of opposed relation to ends of a lower duct, a core extending longitudinally in the bore of said casing and formed with side ports communicating with the lower end of the upper duct and the upper and lower ends of the lower duct, the upper end of the upper duct being unobstructed by said core, packing about said core having tight fitting engagement with walls of the bore of said casing to prevent passage of fluid through the bore of the casing about the core, said core having its upper end adapted to be connected with a reciprocating pump, and valve members mounted 70 in said core and housed by the portions of the core having the side ports communicating with lower ends of the upper and lower ducts, said valve members normally remaining in a lowered

closed position and being shiftable upwardly to an open position and serving to control directional flow of fluid through the core and ducts.

4. A standing valve for a pump comprising a tubular casing having upper and lower ducts 5 extending longitudinally thereof with their ends opening into the bore of the casing and the ends of the upper duct being offset from ends of the lower duct longitudinally of the casing, a core extending longitudinally in the bore of said casing and having its upper end disposed out of blocking relation to the upper end of the upper duct and adapted for connection with a reciprocating pump, said core being formed of sections connected with each other and certain of 15 said sections having side ports communicating with the ducts of the casing, one section having a solid portion constituting a barrier to prevent flow of liquid through the core between the lower end of the upper duct and the upper end of the lower duct, and valve members in said core housed by the portions of the core having ports communicating with lower ends of the upper duct and lower duct and movable from a closed position to an open position.

5. A standing valve for a pump comprising a tubular casing having upper and lower ducts extending longitudinally of the casing and offset relative to each other longitudinally of the casing to dispose their ends out of opposed relation to each other, a hollow core fitting in the bore of said casing and having its upper end out of blocking relation to the upper end of the upper duct and adapted to be connected with a reciprocating pump, said core consisting of a plurality of sections disposed in end to end engagement with each other and threaded to each other, certain of said sections having their walls formed with openings and constituting upper, lower and intermediate cages, the upper cage being disposed in position to communicate with the upper end of the lower duct, the intermediate cage communicating with the lower end of the upper duct and the lower cage communicating with the lower end of the lower duct, tubular 40 valve seats carried by said core and located at lower ends of the intermediate cage and lower cage, valve balls in the intermediate cage and lower cage normally resting upon the valve seats when in a closed position and being shiftable upwardly to an open position, one section having a solid portion constituting a barrier between the upper cage and the intermediate cage, and packing carried by said core to bear against walls of the bore of the casing and prevent flow of fluid 50 through the bore of the casing about the core.

6. A stand valve for a pump comprising a tubular casing, walls of the casing being formed with upper and lower ducts extending longitudinally therein at opposite sides thereof in staggered relation to each other with their ends opening into the bore of the casing in longitudinally offset relation to each other, a hollow core fitting in the bore of said casing and having side ports spaced from each other longitudinally of the core 60 and each communicating with an end of a co-operating duct, a partition blocking the core between the upper end of the lower duct and the lower end of the upper duct, and valves for controlling flow of fluid through the core and the 70 lower ends of the ducts.
